UNITED STATES PATENT OFFICE.

ALBERT R. PRITCHARD, OF ROCHESTER, NEW YORK.

DESIGN FOR A SPRAY-BLOWER BODY.

SPECIFICATION forming part of Design No. 30,531, dated April 11, 1899.

Application filed March 15, 1899. Serial No. 709,218. Term of patent 7 years.

To all whom it may concern:

Be it known that I, ALBERT R. PRITCHARD, a citizen of the United States, and a resident of Rochester, in the county of Monroe and State of New York, have invented and produced a certain new and original Design for a Spray-Blower Body, of which the following is a specification.

This invention relates to a design for a spray-blower body, and the accompanying drawing shows a perspective view thereof.

The leading or material feature of the design resides in the new, useful, and original shape thereof, consisting of the long cylindrical portion A and under the end of the cylindrical portion A the dependent portion B in the form of a double truncated cone having the bases of the two cones coincident, substantially as shown.

What I claim is—

The design for a spray-blower body, substantially as herein shown and described.

ALBERT R. PRITCHARD.
